Patented Dec. 31, 1918.

UNITED STATES PATENT OFFICE.

BERNARD C. BAYNES, OF EXCELSIOR SPRINGS, MISSOURI.

DRAWER-PULL AND TICKET-HOLDER.

1,289,363.

Specification of Letters Patent.

Patented Dec. 31, 1918.

Application filed April 9, 1918. Serial No. 227,541.

To all whom it may concern:

Be it known that I, BERNARD C. BAYNES, a citizen of the United States, residing at Excelsior Springs, in the county of Clay 5 and State of Missouri, have invented certain new and useful Improvements in Drawer-Pulls and Ticket-Holders, of which the following is a specification.

This invention relates to an improved 10 drawer pull and ticket holder and has as its primary object to provide a device of this character which may be attached to the front end of substantially any conventional type of drawer to provide a pull for the 15 drawer and adapted to support a ticket indicating the price of an article or articles contained in the drawer or other desired information concerning the contents of the drawer.

20 The invention has as a further object to provide a device of the above described character which may, if desired, be struck from a single piece of suitable sheet metal and may thus be produced at minimum cost.

25 And the invention has as a still further object to provide a drawer pull embodying a ticket magazine or supplemental ticket holder which may, if desired, be also used for supporting a ticket bearing further indicia concerning the contents of the drawer.

Other and incidental objects will appear as the description proceeds. In the drawings wherein I have illustrated the preferred embodiment of the invention, and 35 wherein similar reference characters designate corresponding parts throughout the several views:

Figure 1 is a fragmentary perspective view showing my improved drawer pull and 40 ticket holder applied to a conventional type of drawer,

Fig. 2 is a vertical sectional view more particularly showing the construction of the ticket holder of the drawer pull as well as 45 the construction and mounting of the ticket magazine,

Fig. 3 is a front elevation showing the ticket magazine in detail, and

Fig. 4 is a vertical sectional view showing 50 a slight modification of the invention wherein the ticket magazine is formed integral with the drawer pull.

Referring more particularly to the drawings, I have shown my improved drawer pull and ticket holder in connection with a conventional type of drawer 10 which is mounted within a suitable casing 11. In carrying out the invention, my improved device is preferably constructed from a single piece of suitable resilient sheet metal 60 bent upon itself to provide a finger receiving portion or body 12 from the ends of which extend lateral side members 13 which are gradually tapered from their lower ends toward their upper ends so that the finger receiving portion 12 is thus inclined downwardly and outwardly with respect to the base edges of the said members. Projecting laterally from the said base edges of these side members are oppositely directed flanges 70 14 which are formed to receive screws or other suitable fastening devices for connecting the pull with the front end of the drawer 10. Thus it will be seen that a person desiring to open the drawer may readily insert 75 the fingers of one hand beneath the finger receiving portion 12 of the pull, for opening the drawer. At its lower margin the finger receiving portion 12 is extended to provide a ticket holding clip 15 rebent upon itself to 80 confront the said finger receiving portion and adapted to coact therewith for receiving the lower margin of a ticket, as conventionally shown at 16, beneath the free extremity of the said clip to be clamped thereby lying flat against the finger receiving portion. The clip will thus firmly support 85 the ticket in position upon the drawer pull for indicating the price of articles contained in the drawer or other information desired concerning the contents of the drawer. At the same time, the presence of the ticket upon the drawer pull will not hamper the use of the pull for opening the drawer nor will such use of the pull be likely to result 90 in displacing the ticket.

It is now to be noted that the upper edge of the finger receiving portion 12 of the drawer pull is spaced from the outer face of the front end of the drawer and mounted upon the said edge of the finger receiving portion is a ticket magazine shown in detail in Fig. 3 of the drawings. This ticket magazine is also preferably formed

from a piece of suitable resilient sheet metal and includes a preferably oblong body 17 of a length slightly greater than the length of the finger receiving portion of the drawer pull and provided at its ends with confronting flanges 18. Depending from the bottom edge of the body adjacent opposite ends thereof are spring arms which are rebent upon themselves to provide resilient loops 19 at the outer ends of which are formed downwardly presented resilient hooks 20. The ticket magazine is, as particularly shown in Fig. 2, rested flat against the front end of the drawer and the loops 19 of the arms thereof inserted between the upper edge of the finger receiving portion 12 of the drawer pull and the end of the drawer to engage the hooks 20 over the upper edges of the finger receiving portion. These hooks 20 are adapted to resiliently coat with the upper margin of the finger receiving portion for clamping the magazine to the drawer pull while the loops 19 will be compressed between the said finger receiving portion and the front end of the drawer for yieldably holding the body of the magazine flat against the front end of the drawer. The ticket magazine will thus be firmly supported in position upon the drawer pull and, as will now be clear, a supply of tickets, as conventionally shown at 21, may be engaged beneath the flanges 18 of the magazine to be carried thereby upon the drawer pull. Accordingly, should the contents of the drawer be changed the ticket 16 may be displaced to be placed within the magazine and a proper ticket removed from the magazine and inserted beneath the ticket holder of the drawer pull. Furthermore, should it be desired to indicate the character of the articles contained in the drawer upon one ticket and the price of such articles upon another ticket, a proper ticket may, as also shown in Fig. 1, be displayed upon the magazine and a price ticket displayed upon the drawer pull. In this connection it will be noted that since the body of the ticket magazine is slightly longer than the drawer pull the lower edges of the tickets 21 will rest upon the upper edges of the side members 13 thereof for supporting the tickets within the magazine. However, should any of the tickets accidentally drop down, loss of such tickets will be prevented by the loops 19 of the arms of the magazine, which loops are adapted to receive the lower margin of any of the tickets displaced.

In Fig. 4 of the drawings I have illustrated a slight modification of the invention wherein the finger receiving portion of the drawer pull is indicated at 22 and the ticket holder of the pull is indicated at 23. Formed integrally with the finger receiving portion is the body 24 of a ticket magazine

which upstands from the finger receiving portion of the drawer pull. In other respects the drawer pull and ticket magazine of this modification are identical with the preferred construction of the invention, the modification relating particularly to the integral formation of the drawer pull and magazine. Further description in connection with the modified construction is accordingly believed unnecessary.

Having thus described the invention, what is claimed as new is:

1. A device of the character described including a drawer pull, means for supporting a ticket upon the drawer pull, and a ticket magazine carried by the drawer pull and adapted to receive a supply of tickets to be selectively engaged with said means.

2. A device of the character described including a drawer pull having a finger receiving portion, and a ticket magazine upstanding from the drawer pull and provided with hooks engaging over the upper edge of the said finger receiving portion of the drawer pull.

3. A device of the character described including a drawer pull having a finger receiving portion, and a ticket magazine upstanding from the drawer pull and including a body, arms extending from the body and rebent to provide loops adapted for engagement between the upper edge of the finger receiving portion of the drawer pull and adjacent face of a drawer for yieldably clamping the body against the said face of the drawer, and hooks carried by the said loops and adapted to engage over the upper edge of the said finger receiving portion for supporting the magazine upon the drawer pull.

4. A device of the character described including a drawer pull having a finger receiving portion, and a ticket magazine carried by the drawer pull and including a body, and means carried by the body for engagement between the finger receiving portion and a drawer for supporting the magazine upon the drawer pull.

5. A device of the character described including a drawer pull having a finger receiving portion, and a ticket magazine carried by the drawer pull and including a body, arms extending from the body, and yieldable means carried by said arms to engage between the finger receiving portion and the drawer pull for supporting the magazine upon the drawer pull.

6. A device of the character described including a drawer pull having a finger receiving portion, side members for supporting the finger receiving portion, and a ticket magazine upstanding from the drawer pull and including a body overhanging said side members, and means carried by the

body for holding a ticket thereon supported against downward displacement from the body by the said side members.

7. In a drawer pull, the combination of 5 a finger receiving portion having an extended lower margin, and a clip formed from said margin and directed upwardly over the

finger receiving portion to yieldably bear against the front face thereof for engagement over a ticket resting against the finger receiving portion and having its lower margin housed beneath the clip. 10

In testimony whereof I affix my signature.
BERNARD C. BAYNES. [L. S.]
